INVENTOR

Frank R. Merritt

UNITED STATES PATENT OFFICE.

FRANK E. MERRITT, OF HAVERHILL, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ABRASIVE TOOL.

1,308,093.

Specification of Letters Patent.

Patented July 1, 1919.

Application filed October 17, 1917. Serial No. 197,152.

To all whom it may concern:

Be it known that I, FRANK R. MERRITT, a citizen of the United States, residing at Haverhill, in the county of Essex and State 5 of Massachusetts, have invented certain Improvements in Abrasive Tools, of which the following description, in connection with the accompanying drawings, is a specification, like reference characters on the drawings 10 indicating like parts in the several figures.

This invention relates to abrading devices and is herein illustrated as embodied in a device for buffing the bottoms of boots and shoes.

15 It is customary to buff the rear part of the shank of the sole of a shoe by means of a circular pad of abrasive material mounted on a holder at the lower end of a rotary shaft, the pad being detachably clamped to the holder so that it may readily be removed and replaced. A pad of this type and its 20 holder and clamping means, which have gone into wide commercial use, are shown in the patent to Rogers, No. 822,154, the pad 25 of the patent comprising a plurality of superposed disks of abrasive material such as sandpaper.

In one form of the patented construction the pad is held in place by a right-angled 30 U-shaped clamping member, the arms or prongs of which extend through holes in the pad and its holder, said member being forced up toward the lower end of the rotary shaft by a screw which passes through the center 35 of its horizontal base and is threaded into the lower end of the shaft. In this construction no upward pull is exerted upon the prongs themselves, their function being merely to serve as additional means for preventing relative rotation between the pad 40 and its holder.

The general object of the present invention is to provide novel and improved means for fastening in place a buffing pad, such for 45 example as that of the patent. To this end one feature of the invention comprises a construction in which the screw or equivalent element of the patent is dispensed with and the prongs of the clamping member are engaged by an adjustable member manipulation of which draws the clamping member upward to clamp the pad to its holder and the holder to the shaft. With this construction not only is the advantage of dispensing

with the screw obtained but the pad is more 55 firmly held.

This and other features of the invention including certain details of construction and combinations of parts will be described as embodied in an illustrative device and will 60 be pointed out in the appended claims.

Referring now to the accompanying drawing:—

Figure 1 is a perspective of a buffing tool in which the present invention is embodied; 65

Fig. 2 is a vertical section of the tool, the shaft and the clamping member being shown in full, and

Fig. 3 is a perspective of the separated parts of the tool. 70

The upright shaft 5 is provided with a pulley 7 which may be driven from any suitable source of power by a belt 9. The lower end of the shaft has an enlarged portion 105 and fitting over this enlarged portion and loose on the main portion of the shaft is an adjusting nut 11 threaded to receive the prongs of the clamping member 13 and counterbored to form a shoulder which engages the upper surface of the enlarged portion 105 of the shaft. The abrasive pad 15 is made of a plurality of superposed disks of sandpaper the diameters of which decrease from bottom to top of the pad, the disks being held together by an 85 eyelet 17. The holder for the pad comprises a piece of felt 19 and a wooden core 21 in the top of which is a socket to receive a projection 205 on the lower end of the shaft so as to center the holder with respect to the 90 shaft. A set of holes 23 extends through the pad and a corresponding set 25 extends through the holder, said holes being located so as to register and to permit the prongs of the clamping member 13 to extend through 95 them and into grooves 305 formed in the shaft 5. The prongs are threaded as shown to correspond to the threads formed on the interior of the adjusting nut 11.

To assemble the device the holder and pad 100 are placed in position on the lower end of the shaft 5, the prongs of the clamping member are passed through the holes 23, 25 and into the grooves 305, and the nut 11 is screwed down thereby drawing up the member 13 to clamp the pad to the holder and the holder to the shaft. To renew the pad when it becomes worn, the nut 11 is un-

screwed until the prongs of the clamping member are released, after which a fresh pad may be put in place.

Having thus described my invention, what

5 I claim as new and desire to secure by Letters Patent of the United States is:—

1. The combination with an abrasive pad, of a rotary member to which the pad is to be fastened, a clamping member having 10 prongs extending through holes in the pad, and means for engaging the prongs and drawing the clamping member against the pad.

2. The combination with an abrasive pad, 15 of a shaft to the end of which the pad is to be fastened, a clamping member having prongs extending through holes in the pad and engaging grooves in the shaft, and adjustable means for engaging the prongs and 20 drawing the clamping member against the pad.

3. The combination with an abrasive pad, of a shaft to the end of which the pad is to be fastened, a clamping member having 25 prongs extending through holes in the pad and engaging grooves in the shaft, and adjustable means carried by the shaft for engaging the prongs and drawing the clamping member against the pad.

30 4. The combination of an abrasive pad, of a holder therefor, a rotary shaft to the end of which the holder is to be fastened, means for centering the holder on the end of the shaft, a clamping member having prongs 35 extending through the pad and the holder,

and means engaging the prongs for drawing the clamping member against the pad to clamp the pad to the holder and the holder to the shaft.

5. The combination with a holder having 40 a set of holes, of an abrasive pad having a corresponding set of holes, a rotary shaft to which the holder and pad are to be fastened, interengaging means on the shaft and holder to position the holder on the shaft, the 45 shaft being provided with grooves which register with the sets of holes, a clamping member having prongs extending through the holes and into the grooves, and means carried by the shaft for engaging the prongs 50 and drawing the clamping member toward the shaft.

6. The combination with an abrasive pad of a shaft to the end of which the pad is to be fastened, a clamping member having 55 threaded prongs extending through holes in the pad and engaging grooves in the shaft, and a nut carried by the shaft and threaded to receive the prongs.

7. The combination with an abrasive pad 60 of a shaft having an enlargement at its lower end, a nut carried by the shaft and having an interior shoulder to engage the enlargement, a pad holder, and a clamping member having prongs extending through 65 the pad and holder, said prongs being threaded for engagement with said nut.

In testimony whereof I have signed my name to this specification.

FRANK R. MERRITT.
